UNITED STATES PATENT OFFICE.

OSCAR H. JUNG, OF MILWAUKEE, WISCONSIN.

FUSE PLUG.

Application filed February 9, 1924. Serial No. 691,621.

To all whom it may concern:

Be it known that I, OSCAR H. JUNG, a citizen of the United States, and resident of Milwaukee, in the county of Milwaukee, 5 and State of Wisconsin, have invented certain new and useful Improvements in Fuse Plugs; and I do hereby declare that the following is a full, clear, and exact description thereof.

10 This invention relates to fuse plugs. As is well known it is difficult to determine, in the usual type of fuse plugs, whether or not the fuse has melted.

Attempts have been made to indicate this 15 condition but these attempts have not wholly met the necessary conditions. For instance, the semi-transparent cap frequently becomes so clouded that it is difficult to tell whether or not the fuse has melted and the various 20 mechanical means heretofore employed have been either too expensive or have been uncertain or unreliable in operation.

This invention is designed to overcome 25 the above noted defects, and objects of such invention are to provide a fuse plug with effective means whereby the integrity of the fuse may be determined, to provide means whereby the testing of the fuse may be quickly made, and to provide a construction 30 of fuse plug which is inexpensive, which is simple, and which is thoroughly reliable in operation.

An embodiment of the invention is shown 35 in the accompanying drawing, in which:—

Figure 1 is a view of a fuse plug with part of the casing broken away to more clearly show the construction.

Figure 2 is a similar view of a modified 40 form.

The fuse plug may be of any of the usual types and comprises a casing 1 on which is carried the screw threaded ferrule 2 and the central contact 3. Within the casing a fuse 4 is positioned and joins the central contact 45 and the ferrule in the usual manner,—it being customary to provide the looped portion 5 of the fuse of a smaller cross sectional arrangement than the remaining portions. The casing 1 is completed in any 50 suitable manner as by means of a metal cap 6 clamped around the edge of the casing as shown. This metal cap is provided with an aperture 7 in the form shown in Figure 1. The indicating means or the testing 55 means for determining the continuity of the

60 fuse may comprise a looped non-combustible member 8 which interlinks with the fuse 5 and has its ends projecting through the aperture 7 in the cap 6. The ends are bound together or permanently joined by 65 means of a member 9 which may be formed in any suitable manner. This member may be a knot tied in the strings 8, for instance, or may be an enlargement such as sealing wax or a metal cap. It is indicated generally at 9 in Figure 1.

The operation of the apparatus is as follows:—When it is desired to test whether or not the fuse has melted, it is merely necessary to grasp the member 9 and pull upon 70 the looped strands 8. If the fuse has melted the member 8 may be readily withdrawn, whereas on the other hand if the fuse is still continuous, the withdrawal of the member 8 is prevented. It is well known that these 75 fuse plugs are usually installed in a relatively poorly lighted place, and in an out of the way place, thus it is difficult to determine whether or not the fuse is still effective. However, with this invention, the operator may quickly test the several fuse 80 plugs and may easily locate the melted fuse.

The member 8 may be of any suitable material which is preferably non-combustible. 85 A convenient material for this use is asbestos, although, obviously, other materials could be employed. It is also to be noted that the member 8 does not form a hermetical seal for the aperture 7 but that there is 90 in effect a vent for the expanding gases due to the melting of the fuse and the heat incident thereto.

In the form shown in Figure 2, the same 95 general construction of fuse plug is employed as that previously described. The metal cap 6', however, is imperforate in this form of the invention, and an aperture 10 is formed adjacent the outer end of the cylindrical casing 1. Through this aperture the looped member 8' is passed and is preferably 100 provided with binding portion 9' joining the terminals of the strand.

It is to be noted that the direction of pull 105 of the member 8' is slanting with reference to the axis of the fuse plug and is directly away from the general line of the two loops of the fuse.

It will be seen from the description and drawings that an extremely simple and very 110 cheap form of testing means or indicating

means has been provided which is thoroughly reliable in operation; and which may be quickly manipulated.

Although the invention has been described in considerable detail, it is to be understood that the invention may be variously embodied and is, therefore, to be limited only as claimed.

I claim:

10. A screw plug fuse comprising a body portion having a cylindrical shell, a threaded ferrule surrounding said shell, a central contact located at the forward end of said body portion, a fusible element having one end secured to said central contact and the other
- 15.

end secured to said ferrule and having a rearwardly extending looped portion, a non-combustible flexible member passing through said loop and extending outwardly from said body portion and adapted to be drawn rearwardly to test the continuity of said fusible element, whereby when said member is drawn upon the stress is transmitted longitudinally to both strands of said fusible element.

In testimony that I claim the foregoing I have hereunto set my hand at Milwaukee, in the county of Milwaukee and State of Wisconsin.

OSCAR H. JUNG.
